UNITED STATES PATENT OFFICE.

CHARLES FRANZ, OF NEW YORK, N. Y., ASSIGNOR TO A. A. VANTINE & CO., OF SAME PLACE.

DESIGN FOR WOVEN FABRIC.

SPECIFICATION forming part of Design No. 29,859, dated December 20, 1898.

Application filed November 21, 1898. Serial No. 697,098. Term of patent 31 years.

To all whom it may concern:

Be it known that I, CHARLES FRANZ, a subject of His Majesty the Emperor of Germany, residing at Jamaica, borough of Queens, city 5 and State of New York, have invented and produced a new and original Design for a Woven Fabric, of which the following is a specification, reference being had to the accompanying drawing, forming part thereof, 10 in which is represented a plan view of a piece of fabric embodying my design.

The leading feature of the design consists of five panels A B C D E, drawn to show that each is sewed together with a heavy stitch and 15 all running in a perpendicular manner. Panel A is made up to contain a number of Turkish and Moorish symbols, figures F G H I J K, and decorated with smaller figures L M N. Each of the figures is drawn so as to have the 20 effect of stitchwork and finished off with a

border of Turkish letters on each side, O, P, Q, and R.

Another feature of the design consists of panels C and E, both being identical in every respect to panel A. Other features of the 25 design consist of panels B and D, wherein the figures F G H and the smaller figures L and M, as in the panels A, C, and E, are transferred to the lower half of panel and the figures I J K and smaller figures M and L, as 30 in panels A, C, and E, are transferred to the top half of panel, the whole design having an oriental Turkish-stitch effect throughout.

I claim—

The design for a woven fabric herein shown 35 and described.

CHARLES FRANZ.
